DESIGN FOR A CHAIR

William J. Hickerson, Philadelphia, Pa.

Application June 13, 1938, Serial No. 77,799

Term of patent 3½ years

To all whom it may concern:

Be it known that I, William J. Hickerson, a citizen of the United States of America, residing at Philadelphia, in the county of Philadelphia and State of Pennsylvania, have invented a new, original, and ornamental Design for a Chair, of which the following is a specification, reference being had to the accompanying drawing, forming part thereof, in which the drawing represents a perspective view of a chair showing my new design.

I claim:

The ornamental design for a chair, as shown.
WILLIAM J. HICKERSON.
